UNITED STATES PATENT OFFICE.

THOMAS F. STUBBLEFIELD, OF MEMPHIS, TENNESSEE.

REVOLVING ADVERTISING DEVICE.

1,233,931.

Specification of Letters Patent.

Patented July 17, 1917.

Application filed December 7, 1915. Serial No. 65,531.

To all whom it may concern:

Be it known that I, THOMAS F. STUBBLEFIELD, a citizen of the United States, residing at Memphis, in the county of Shelby and State of Tennessee, have invented certain new and useful Improvements in Revolving Advertising Devices; and I do hereby declare the following to be a full, clear, and exact description of the invention, such as will enable others skilled in the art to which it appertains to make and use the same.

The invention relates to improvements in revolving advertising devices.

15 The object of the present invention is to improve the construction of revolving advertising devices and to provide a simple, practical and comparatively inexpensive advertising device designed for use in show windows and various other places and equipped with advertising cards adapted through the rotary movement of the device to reverse themselves automatically so as to display both sides of the card at intervals.

25 A further object of the device is to provide a rotary advertising device of this character adapted to be read from either side, that is to say, from the front or back of the advertising device and equipped with 30 clock mechanism and adapted to catch the eye and hold the attention while the advertising wheel is making a complete revolution or until it has displayed its entire advertising matter.

35 It is also an object of the invention to provide a rotary advertising device of this character adapted to afford a maximum advertising space and adapted to permit the cards to be removed and replaced without 40 stopping the device.

With these and other objects in view the invention consists in the construction and novel combination and arrangement of parts hereinafter fully described, illustrated in 45 the accompanying drawings and pointed out in the claims hereto appended, it being understood that various changes in the form, proportion and minor details of construction may be resorted to without departing from 50 the spirit or sacrificing any of the advantages of the invention.

In the drawings—

Figure 1 is a front elevation of an adver-

tising device constructed in accordance with this invention,

55

Fig. 2 is a central vertical sectional view of the same,

Fig. 3 is a transverse sectional view on the line 3—3 of Fig. 2,

60

Fig. 4 is a similar view on the line 4—4 of Fig. 2,

Fig. 5 is a transverse sectional view on the line 5—5 of Fig. 2,

65

Fig. 6 is a transverse sectional view on the line 6—6 of Fig. 2,

Fig. 7 is a detail sectional view on the line 7—7 of Fig. 2,

70

Fig. 8 is a detail sectional view on the line 8—8 of Fig. 2 illustrating the construction of the winding mechanism,

Fig. 9 is a detail perspective view of one of the pivoted gravity acting reversible card holders.

Like numerals of reference designate corresponding parts in the several figures of the drawings.

In the accompanying drawings in which is illustrated the preferred embodiment of the invention, the rotary advertising device comprises in its construction, a main drive wheel 1 mounted on a hollow shaft 2 and having internal gear teeth and connected by a train of gears with an inner horizontal shaft or axis 4 arranged within the hollow shaft 2. The hollow shaft carries 85 the hour hand 6 and the inner shaft 4 carries the minute hand 5. The teeth of the train of gears being proportioned to cause the hour hand to travel one-twelfth as fast as the minute hand. The hollow shaft is 90 journaled in suitable bearings of a frame composed of front disk or plate 7 and a rear disk or plate 8 connected with the front plate by bars 9 which have terminal attaching portions 10 for securing the main or supporting 95 frame to a suitable support. The disks or plates 7 and 8 are preferably open as shown but any other suitable supporting frame may of course be employed. The train of gears for connecting the main drive wheel 100 with the inner minute hand shaft consists of inner, outer and intermediate gears 11, 12 and 13 meshing with each other as clearly illustrated in Fig. 4 of the drawings, the inner gear 11 being mounted on the shaft 4 105 and the outer and intermediate gears 12 and

13 being arranged on shafts or arbors 14 and 15 supported by the rear disk or plate 8 of the main or supporting frame and a plate 16 arranged within the main or supporting frame and suitably secured to the said rear plate with its body portion in spaced relation with the same.

The main drive wheel which may be spring actuated is illustrated in the drawings as actuated by a weight 17 connected to one end of a cord 18 which has its other end connected with and adapted to be wound on a cylinder or drum 19 mounted on the shaft 2 and provided with front and rear rims, the rear rim being provided with ratchet teeth 20, which are adapted to be engaged by a spring actuated pawl or dog 21 that is carried by the main drive wheel. This provides a ratchet or clutch connection between the drum and the main drive wheel to enable the drum to be rotated independently of the main or drive wheel for winding up the weight or spring. The front rim of the drum is provided with bevel gear teeth 22 which meshes with a bevel pinion 23 of a winding shaft 24 journaled in suitable bearings of the front disk or plate 7 of the main or supporting frame and provided at its outer end with a suitable handle or grip 25. The winding shaft 24 is adapted to be rotated to turn the drum or cylinder on the shaft 2 for winding up the weight but any other suitable means may of course be employed for effecting this operation of rewinding the clock mechanism. The winding shaft extends beyond the periphery of the supporting frame and is adapted to be readily grasped to rotate the drum or cylinder which is interposed between the main drive wheel and the front disk or plate 7.

Mounted upon the main hollow shaft 2 which carries the hour hand 6 is an escape wheel 26 which is provided with a substantially annular slot or opening 27 composed of straight angularly related portions forming inner and outer scalloped edges 28 and 29 which are adapted to engage a detent 30 of a pendulum 31 pivotally mounted at 32 on a suitable pin or pivot and preferably of a length to oscillate during the period of a second and the angularly disposed portions and scalloped edges are of sufficient number to cause the escape wheel to make one complete revolution during the period of a minute.

The escape wheel imparts periodic impulses to the pendulum which alternately engages the inner and outer edges of the angularly related slots of the escape wheel. The detent 30 of the pendulum is approximately L-shaped and consists of an arm having a laterally projecting terminal portion 33 which extends between the inner and outer scallops or angularly related edges of the escape wheel.

The escape wheel which is loosely mounted on the hour hand shaft 2 is connected with the inner or minute hand shaft 4 by a train of gears consisting of a pinion 34 mounted on the hub 35 of the escape wheel and meshing with a gear wheel 36 fixed to a shaft or arbor 37 which is journaled in suitable bearings of the front and rear disks or plates of the main or supporting frame. The shaft or arbor 37 has keyed or otherwise secured to its rear end a pinion 38 which meshes with a gear wheel 39 mounted on the rear end of the shaft 4. The train of gears is properly proportioned so that the minute hand shaft will travel at the proper rate of speed, with relation to the rotation of the escape wheel.

The escape wheel is connected with a rotary advertising wheel or frame 40 preferably consisting of spokes 41, and inner and outer concentric rims 42 and 43 suitably secured to the spokes which are attached to the escape wheel. The advertising wheel which may be of any other desired form has inwardly tapered openings 44 in which are pivoted holders 45 composed of inner and outer arms 46 and 47 having radially aligned pivots 48 and 49 which are mounted in suitable bearing openings in the inner and outer rims.

The pivots are disposed centrally of the inner and outer ends of the tapered faces and the arms terminate short of one side of the faces so that the transverse connecting portions 45 and the arms constitute a gravity acting holder which has grooves 50 for the reception of cards 51 but plates or any other suitable means may of course be employed to form pivotal gravity acting members or sections.

The cards are designed to be provided at their front and rear faces with advertising or other matter to be displayed and the cards may be viewed from the front or back of the device as they lie beyond the front mechanism. Also the gravity acting holders are adapted to reverse automatically as they reach the top and bottom of the wheel whereby each face of each card will be displayed during a portion of the rotation of the advertising wheel. Also the free pivotal movement of the holders will enable the contents thereof to be readily changed without stopping the advertising device.

The advertising device is provided with a dial 52 which may be maintained stationary in any suitable manner.

The dial 52 is supported by upper and lower braces 53 secured to the support on which the advertising device is mounted and extending therefrom to the dial at the top and bottom thereof as clearly shown in Fig. 2. These braces by being arranged at the top and bottom of the advertising device

may be conveniently employed for concealing the pivoted cards and their holders while the same are being reversed.

What is claimed is:—

5 1. A device of the class described including a rotary wheel or carrier and gravity actuated devices pivotally mounted on radially arranged axes and automatically reversible to present their opposite faces to 10 the front.

2. A device of the class described including a vertically disposed rotary wheel or carrier and devices carried by the rotary wheel or carrier and pivotally mounted on 15 radially arranged axes and automatically reversible when they reach the top and bottom of the said wheel or carrier to present their opposite faces to the front.

3. A device of the class described including a vertically disposed rotary wheel or carrier provided with a plurality of inwardly tapered radially arranged openings, means for pivotally mounting sections on 20 radially arranged axes in the said openings, said sections being adapted to have advertising and other matter at their front and rear faces, and means for automatically reversing the sections to present their front and rear faces periodically during the 25 rotation of the wheel or carrier.

4. A device of the class described including a vertically disposed advertising wheel provided with an annular series of inwardly tapered radially arranged openings, sections 30 arranged in the said openings, means for pivotally mounting the sections in the said openings on axes arranged radially of the

wheel, said sections being weighted at one side of the center whereby they are caused to reverse automatically at the top and 40 bottom of the wheel during the rotation thereof.

5. A device of the class described including a rotary carrier, and a holder of approximately U-shape composed of inner and outer arms and a connecting portion, said 45 arms being provided with alined pivots arranged radially with respect to the rotary carrier and mounted thereon, and a card removably mounted in the said holder between 50 the arms thereof.

6. A device of the class described including a rotary carrier, and a holder of approximately U-shape composed of inner and outer arms and a connecting portion, said 55 arms being provided with alined pivots arranged radially with relation to the rotary carrier and mounted on the same, said holder being provided in its arms and connecting portions with grooves adapted to receive a 60 card.

7. A device of the class described including a vertically disposed rotary carrier, and an annular series of automatically reversible gravity acting sections pivotally mounted in 65 the said openings on axes arranged radially of the rotary carrier.

In testimony whereof I affix my signature in presence of two witnesses.

THOMAS F. STUBBLEFIELD.
